UNITED STATES PATENT OFFICE.

CHARLES W. ARMBRUST, OF CRYSTAL LAKE, ILLINOIS, ASSIGNOR OF ONE-FOURTH TO
SYDNEY STEIN, OF CHICAGO, ILLINOIS.

BRAKE-SHOE.

1,010,398.

Specification of Letters Patent. Patented Nov. 28, 1911.

Original application filed January 18, 1911, Serial No. 603,268. Divided and this application filed March 8, 1911. Serial No. 613,610.

To all whom it may concern:

Be it known that I, CHARLES W. ARMBRUST, a citizen of the United States, residing at Crystal Lake, in the county of McHenry and State of Illinois, have invented certain new and useful Improvements in Brake-Shoes, of which the following is a specification.

This invention relates to brake shoes and more particularly to that type of brake shoe known as interlocking shoes, wherein the backs and faces of similar shoes are provided with interengaging means so that a partially worn shoe may be applied to the wearing face of a new shoe thereby enabling the worn shoe to be completely used up, and the present application is a division of my copending application Serial No. 603,268, filed January 18th, 1911.

One of the objects of the present invention is the provision of an interlocking shoe wherein the interlocking parts on the back and face of similar shoes are constructed to be engaged in interlocking relation by moving one of the shoes transversely relatively to the other, the shoes being so shaped that when interlockingly engaged the portions thereof intermediate the ends are spaced apart.

Another object of this invention is the provision of a shoe having end guide lugs and thrust lugs adapted to coöperate with the end prongs of a brake head to maintain the shoe in alinement but not having the usual central holding or fastening lug by means of which the shoe is attached to the brake head. By providing upon the center of the back of the shoe a shallow locking stud or lug adapted to be engaged by a detachable holding or fastening lug I am enabled to make the central locking recess on the face of the shoe much shallower than would be required to receive a locking or fastening lug made integral with the body of the shoe. This reduction of the depth of the central locking recess permits the greatest amount of material to be incorporated in a shoe of predetermined thickness, producing a shoe of maximum transverse strength.

Other objects and advantages of the present invention will be apparent as it is better understood by reference to the following description when taken in connection with

the accompanying drawings illustrating one preferred embodiment thereof.

Referring to the drawings—Figure 1 is a side elevation of an interlocking shoe embodying my invention. Fig. 2 is a top plan view thereof. Fig. 3 is a face view; Fig. 4 is a sectional view on the line 4—4 of Fig. 1, and Fig. 5 is a fragmentary view of a modified form of shoe.

On the drawings 5 designates the main body member of a shoe provided on its back with an integral centrally disposed locking stud or lug 6, the sides of which are undercut, as indicated, at 7, for interlocking engagement with a detachable holding or fastening lug 8, shown in dotted lines in Fig. 1. The thrust lugs 9 formed integrally with the shoe body are arranged transversely of the back of the shoe preferably at the ends thereof, and adjacent the thrust lugs are formed the guide lugs 10 disposed upon the longitudinal axis of the shoe. The guide lugs are of proper width to fit snugly between the end prongs of a brake head and coöperate therewith to maintain the shoe in alinement, while the thrust lugs are positioned to engage the outer ends of the brake head end prongs. Upon the back of the shoe and intermediate the central locking lug and the end guide and thrust lugs, are arranged the locking lugs 11 which extend transversely of the shoe body and have their longitudinal sides undercut similarly to the central locking lug or stud.

The face of the shoe is provided with a central locking recess 12 having undercut walls for locking engagement with the central locking lug or stud 6 of a similarly shaped shoe, and undercut recesses 13 for locking engagement with similarly shaped locking lugs 14. The ends of the shoe are provided with depressions adapted for the reception of the thrust lugs 9 and with shallower depressions 15 for the accommodation of the guide lugs 10. It will be observed that the locking lugs 6 and 11 and the thrust lugs 9 do not extend entirely across the back of the shoe but terminate at each end short of the sides of the shoe body. It will be observed also that the locking recesses 12 and 13 and the depressions 14 are open at one end to receive the locking lugs and thrust lugs and are closed at their other ends to prevent lateral displacement.

of the worn shoe beyond that side of the fixed shoe. The shoes are fastened to the brake head with the closed ends of the recesses disposed outwardly, the open ends of 5 the recesses lying adjacent the flange of the wheel which is relied upon to prevent lateral displacement of the worn shoe inwardly. The depressions 15 are shown as extending only partially across the face of 10 the shoe and a sufficient distance to receive the axially disposed guide lugs 10.

It will be evident from an inspection of Fig. 1 that the backs and faces of the shoes are formed on the arcs of concentric circles 15 of different radii, the back of the shoe being formed on the arc of a circle having a greater radius than the circle upon which the face of the shoe is formed. This construction permits the back and face of interlocked shoes to be spaced apart so that the locking recesses 12 and 13 may be made shallower than would be possible if the back and face of the interlocked shoes lay flush against each other throughout their 25 length. The locking recesses are accordingly made of less depth than the locking lugs 6 and 11, thus enabling the lugs to serve as spacing lugs to space the back and face of the shoes apart as well as locking 30 lugs to lock the shoes together. The depressions 14 and 15 are also slightly shallower than the thrust and guide lugs 9 and 10 so that these lugs serve to space the ends of the shoes apart when they are interlocking 35 engaged. By making the recesses on the face of the shoes as shallow as is consistent with the locking of the shoes together the maximum amount of material may be incorporated in a shoe of a predetermined thickness; and furthermore the spacing of the shoes permits the entire body of the acting shoe to be worn away before any portion of the back shoe is brought into contact with the wheel.

40 45 In the modification disclosed in Fig. 5 the inner end of the guide lug 10' and the outer side of the thrust lug 9' are undercut. The depression 14 shown in the previous modification has an outer wall 16 undercut to engage the under cut lug 9' and the inner wall of the recess 15 is also undercut to engage with the under cut lug 10'. By this construction the guide and thrust lugs are adapted to serve also as spacing 50 55 lugs.

From the foregoing it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

I claim:

1. An interlocking brake shoe comprising a body member provided on its back with end guide and thrust lugs, and centrally disposed means homogeneous with the body of the shoe to permit attachment thereto and detachment therefrom of a brake shoe fastening or holding lug. 70

2. An interlocking brake shoe comprising a body member provided on its back with end guide and thrust lugs, and centrally disposed means adapted for successive attachment thereto and detachment therefrom, of an integral fastening or holding lug and having on its face depressions adapted to receive the guide and thrust lugs and centrally disposed means of a similarly shaped shoe. 75

3. An interlocking brake shoe comprising a body member provided on its back with end guide and thrust lugs, locking lugs, and centrally disposed means for the attachment of a fastening or holding lug. 80

4. An interlocking brake shoe comprising a body member provided on its back with guide lugs, thrust lugs, locking lugs and centrally disposed means for the attachment of a fastening or holding lug, and having on its face recesses for interlocking engagement with the locking lugs and centrally disposed means of a similarly shaped shoe. 85

5. An interlocking brake shoe comprising a body member provided on its back with a centrally disposed stud adapted to be engaged by an attaching lug detachable from said stud, and guide and thrust lugs disposed adjacent the ends of the body member, the face of said member being provided with recesses to accommodate said stud, guide lugs and thrust lugs. 90

6. An interlocking brake shoe comprising a body member having the back and face thereof formed on the arcs of different circles, the back of the shoe being provided with lugs and the face of the shoe being provided with recesses to receive the lugs of a similarly shaped shoe, said recesses being shallower than the lugs engaged therein, whereby the face and back of the interlocking shoes are spaced apart throughout their length. 10

7. An interlocking brake shoe comprising a body member having lugs on its back and recesses on its face to interlock with the lugs of a similar shoe, the curvature of the face of the shoe being greater than the curvature of the back thereof, said recesses being shallower than the lugs engaged therewith, whereby the back and face of interlocked shoes are spaced apart throughout their length. 11

8. An interlocking brake shoe comprising a body member provided with depressions on its face and having means on its back to engage with the depressions in a similarly shaped shoe whereby the shoes are 12

locked together and spaced apart throughout their entire length.

9. An interlocking brake shoe, comprising a body member provided on its back with end guide and thrust lugs and on its face with recesses to receive the guide and thrust lugs of a similarly shaped shoe, said guide and thrust lugs and the walls of said recesses being undercut to form an interlocking engagement between the shoes.

10. An interlocking brake shoe, comprising a body member provided on its back

with end guide and thrust lugs and with centrally disposed means for the attachment of a detachable fastening or holding lug, 15 the transversely extending walls of said guide and thrust lugs being undercut to interlockingly engage the undercut recesses on the face of a similarly shaped shoe.

CHARLES W. ARMBRUST.
